SAFETY ATTACHMENT FOR WRINGERS

Morris Feldman, Baltimore, Md.

Application February 28, 1934, Serial No. 713,411
Renewed July 15, 1935

1 Claim. (Cl. 68—32)

This invention appertains to new and useful improvements in washing machine wringers, and more particularly to a safety attachment whereby the likelihood of injury occasioned by the operator's fingers being caught between the rollers of the wringer, is substantially eliminated.

Another important object of the present invention is to provide a safety attachment for wringers which can be readily applied to the conventional wringer assembly without altering the present construction.

Still another important object of the present invention is to provide a safety attachment for wringers wherein means is provided which will release the pressure roller of the wringer, and will also tend to urge the hand away from the wringer rolls before the fingers are actually caught.

Other important objects and advantages of the invention will become apparent to the reader of the following specification.

In the drawings:—

Figure 1 represents a side elevational view of a conventional wringer assembly, showing the attachment secured to the opposite side thereof.

Figure 2 represents a horizontal sectional view taken substantially on line 2—2 of Figure 1.

Figure 3 represents a vertical sectional view through the attachment.

Figure 4 represents a vertical transverse sectional view through the wringer and attachment, taken substantially on line 4—4 of Figure 1.

Figure 5 represents a fragmentary detailed sectional view taken substantially on line 5—5 of Figure 1.

Figure 6 represents a fragmentary detailed sectional view showing the adjustment for one of the riders.

Figure 7 represents a perspective view of the horizontal connecting shaft.

Figure 8 represents a perspective view of the pressure roll releasing handle engaging member.

Referring to the drawings wherein like numerals designate like parts, it can be seen in Figure 1 that numeral 5 represents generally the conventional wringer which consists of a frame 6 in which is mounted the usual drive roll 7 and pressure roll 8. The pressure roll 8 has its bearing blocks engaged by an elongated strip spring 9 located in the hinged, hollow upper portion 10 of the frame. The free end of this hinged portion 10 is secured to the frame proper 6 by a latch 11 and this latch can be released by the handle 12. This construction is conventional and now on the market. The spring 9 can be

adjusted, as is well known, by a suitable screw 13 or other suitable means.

The attachment is generally referred to in Figures 3 and 4 by numeral 14 and consists of an inverted U-shaped and substantially hollow frame 5 15, in the depending leg portions of which are the bearing blocks 16—16 upon which the shaft ends of the lower fixed roll 17 rests, while above the blocks 16—16 are the blocks 17'—17', which have seats 18 therein for receiving the shaft ends 10 of the upper mobile roll 19. A shoulder 19' is provided at one side of the seat on each block 17 and this shoulder has an overhanging portion 20 with respect to the shaft end 21 of the roll 19 so that in the event the roll 19 is forced upwardly, the shaft end 21 in riding against the overhanging shoulder portion 20 will be moved in the direction of the arrow in Figure 5, that is, in the direction of the pressure roll 8 of the wringer.

Resting upon each of the shaft ends 21 is a 20 rider 22 which is provided with a countersunk opening therein through which extends the threaded barrel 23. A nut 24 is engageable on this threaded barrel and against the rider 22 to retain the barrel positively connected to the rider. 25 The barrel 23 is internally threaded to receive the threaded end 25 of the rod 26 which extends upwardly and connects to the laterally disposed arm 27 at the corresponding end of the shaft 28, which shaft is journaled through suitable bearing 30 elements 29.

A bracket 30 in the upper portion of the frame 15 rotatably supports a member 31 which is provided with a laterally disposed portion 32 having a foot 33 engageable with the adjacent arm 27 35 of the shaft 28, while the opposite end of the member 31 is provided with an upwardly disposed portion 34 extending through an opening 35 in the upper portion of the frame 15 and an obliquely disposed extension 36 which is disposed 40 over the handle 12 on the conventional wringer.

As is clearly shown in Figure 4, the upper mobile roll 19 is in close proximity to the pressure roll 8 of the wringer. A suitable guide bar 37 can be interposed between the drive roll 7 of 45 the wringer and the fixed roll 17 of the attachment so that material can be well guided toward the wringer rolls.

In operation of the attachment, material is fed between the rolls 17—19 and permitted to be 50 caught between the wringer rolls. In the event, the operator's hand starts between the rolls 17 and 19, the upper roll 19, being free to rise, will be forced upwardly by the hand and in riding against the overhanging shoulder portion 20, of 55

the bearing blocks 17', the shaft ends 21 will cause the roller 19 to move toward the pressure roll 8, and as the pressure roll 8 is moving in the direction of the arrow in Figure 4, when the roll 19 engages the same, the roll 19 will be driven in the opposite direction so that there is a tendency of the roll 19 to force the hand out from between the rolls 17-19.

Simultaneously with this action of the roll 19, 10 the rod 26 lifts, while it rotates the shaft 28 and causes actuation of the member 31, which in turn throws its extension 36 downwardly and exerts pressure against the handle 12 so that the handle releases the catch 11 and permits the 15 hinged section 10 of the wringer frame 6 to fly up, thus releasing the tension of the spring from the pressure roll 8.

While the foregoing specification sets forth the

invention in specific terms, it is to be understood that numerous changes in the shape, size and materials may be resorted to without departing from the spirit and scope of the invention as claimed hereinafter.

Having described the invention, what is claimed as new is:—

In a wringer including a pressure roll and a drive roll and means for releasing the pressure from the pressure roll; a pair of auxiliary rolls, 10 one of said rolls being an idler, the other roll being vertically movable, guide means for moving the last mentioned roll toward the pressure roll to engage the latter when the former is moved vertically, and means engaged by the said vertically movable roll for actuating the said pressure releasing means of the pressure roll.

MORRIS FELDMAN.
